UNITED STATES PATENT OFFICE.

EBEN R. PACKER, OF WILMETTE, ILLINOIS.

RAILWAY SNOW-FLANGER.

1,162,096.

Specification of Letters Patent. Patented Nov. 30, 1915.

Application filed September 13, 1915. Serial No. 50,348.

To all whom it may concern:

Be it known that I, EBEN R. PACKER, a citizen of the United States, residing at Wilmette, county of Cook, State of Illinois, have 5 invented a certain new and useful Improvement in Railway Snow-Flangers, and declare the following to be a full, clear, and exact description of the same, such as will enable others skilled in the art to which it pertains 10 to make and use the same, reference being had to the accompanying drawings, which form a part of this specification.

In my prior Patent No. 1,057,084 dated March 25, 1913, I have disclosed and claimed 15 a new type of snow flanger, that is a mechanism adapted for use on railway cars or locomotives for the purpose of clearing the rails of snow and ice.

The present invention has for its object 20 to improve my prior flanger in certain respects. Thus in the flanger of my aforesaid patent the blades or wings which are adapted to be let down over the tops of the rails to remove the snow and ice are normally 25 held in raised idle positions by pneumatic pressure and are only lowered into their working positions when the air is exhausted. This arrangement makes it possible for the flanger to be dropped down on the rails accidentally in case there is failure of the air 30 pressure, and this might not be discovered until damage had resulted by reason of the flanger catching in a switch or other obstruction.

35 One of the purposes of my invention is to overcome this objection to my prior flanger and to make it as safe as possible and not liable accidentally to drop down into its working position.

40 Furthermore, in the arrangement shown in my aforesaid patent, where the flanger is mounted on the truck of a locomotive special equalizing plates are employed, these being substituted for the usual equalizing 45 plates present in the truck.

Another feature of my present invention is to do away with the necessity for disturbing the equalizer plates of locomotive trucks and make the connection between the 50 flanger and the truck extremely simple.

The various features of novelty whereby my invention is characterized will herein-after be pointed out with particularity in the claims; but, for a full understanding of 55 my invention and of its objects and advan-

tages, reference may be had to the following detailed description taken in connection with the accompanying drawings, wherein:

Figure 1 is a top plan view of a flanger and its supporting device arranged in accordance with a preferred form of my invention, a portion of the locomotive truck being shown in dotted lines; Fig. 2 is a front view of the mechanism shown in Fig. 1, a part of one of the wings being broken away; 60 Fig. 3 is a section taken approximately on line 3—3 of Fig. 1, showing the relation of the flanger to the locomotive pilot; Fig. 4 is a detail on a slightly enlarged scale showing one of the pneumatic actuating devices 70 for the flanger in position to hold the flanger down; and Fig. 5 is a view similar to Fig. 4, showing the normal condition of the pneumatic actuating device when the air supply is exhausted. 75

In my prior patent above noted I have illustrated my flanger as embodied in various different specific forms. For the sake of brevity I have selected for the purpose of illustrating the improvements in my prior 80 flanger only a single form and I desire to have it understood that I do not intend to be limited to the single form so illustrated, but intend to cover my improvements as applied to all of my various forms of flangers shown 85 in the aforesaid patent and also to that form in which the blades or wings extend entirely across the track and thus form a plow in addition to performing their functions of 90 cleaning the snow and ice from the rails themselves. 95

Reference being had to the drawings, 1 and 2 are brackets the rear portions of which are shaped to take the place of and serve the same purpose as the front pedestal of two of the journal boxes of a locomotive truck. In order to apply the flanger to a truck, the two front pedestals are removed and the two brackets are put in their place. The brackets are provided with elongated vertical or substantially vertical slots, 3, through which extends a transverse bar or cross piece, 4, having at its ends the flanger wings or blades, 5. The two brackets are connected together by means of a horizontal cross brace, 6, which lies slightly in front of the brackets and near the lower ends thereof; the ends, 7, of the brace being bent rearwardly so as to overlap the brackets, and being suitably fastened thereto by means of 100 105 110

bolts, 8, or the like. The lifting and lowering mechanism for the flanger is arranged between the bar 4 and the brace 6, consisting of one or more pneumatic engines or 5 motors. In the arrangement shown there are two of these pneumatic devices, one arranged near each side. The pneumatic devices consist of pistons, 9, whose rods or stems, 10, are arranged vertically above the 10 brace 6 and have their lower ends rigidly connected thereto; together with cylinder members, 11, connected to and movable with the cross bar 4 and operatively related to the pistons. The cylinders are made long 15 enough to provide room therein above the pistons for strong compression springs, 12, which, when free to do so, expand and raise the cylinders and with them the cross bar and the flanging blades or wings, so as to 20 hold the blades or wings in their inoperative positions above the rails. This condition is illustrated in Fig. 5, where the spring is shown expanded far enough to force the cylinder up until the piston is located in the 25 extreme lower end of the cylinder.

A suitable flexible connection, 14, is provided for admitting compressed air into the cylinders beneath the pistons. This connection may be the same as in my prior patent 30 and therefore requires no explanation. When no air is being supplied through the connection, either because the air has been shut off or because an air pipe has accidentally become broken and therefore allowed 35 the air to escape, the parts occupy the positions indicated in Fig. 5 and hold the flanger in its idle raised position. When it is desired to lower the flanger in operative relation to the rails, in order to clean the rails 40 or the track in case the flanger be in the form of a plow, air is supplied through the connection 14 and it enters the cylinders beneath the pistons where it exerts sufficient pressure to overcome the tension of the 45 springs 12 above the pistons and consequently draws the cylinders down and lowers

the flanger as indicated in Fig. 4 and also in Figs. 2 and 3.

It will thus be seen that the normal condition of the flanger is that of being elevated clear of the track and it will always return to this condition upon failure of the air pressure. Consequently the existence of a supply of air is not essential for the purpose of keeping the flanger in a position 55 where it cannot accidentally do any harm, but is only required for the purpose of bringing the flanger into its working position.

I claim:

1. A snow flanger attachment for locomotive trucks comprising a frame having portions constructed and arranged to take the place of two of the pedestals of the truck journal boxes, and a flanger carried by said 65 frame.

2. The combination with a railway vehicle, of a supporting frame carried thereby, a snow flanger, a vertical cylinder connected to the flanger, a piston supported by said 70 frame, a spring in the cylinder above the piston tending normally to raise the cylinder, and means for admitting fluid under pressure into the cylinder beneath the piston.

3. A snow-removing attachment for rail- 75 way vehicles, comprising a frame, a cross bar mounted on said frame so as to be movable in the vertical direction, means on the frame for removing snow from the track, a coöperating piston member and cylinder 80 member arranged between said cross bar and said frame, a spring within the cylinder for producing a relative movement between the piston and the cylinder in the direction to lift the cross bar, and means for introducing 85 fluid under pressure into the cylinder to produce a relative movement between the piston and the cylinder in a direction to lower the cross bar against the tension of said spring.

In testimony whereof I sign this specifica- 90 tion.

EBEN R. PACKER.
